HYDRAULIC PUMP

Douglas Gerhard Booth, Ilford, England, assignor
to The Plessey Company Limited, Ilford, Eng-
land, a British company

Application February 24, 1945, Serial No. 579,658
In Great Britain March 3, 1944

5 Claims. (Cl. 103—11)

1

This invention relates to improvements in hydraulic double acting pumps which operate over a wide range of high pressures more especially, but not exclusively, to the kind which are operated manually.

Hitherto, in pumps of the kind referred to, the capacity is comparatively small in order to obtain a reasonable working effort on the operating handle or the like, by reason of the fact, that as the pressure increases there is a corresponding increase in the operating effort, consequently, a larger volume cannot be pumped at a lower pressure. If a large capacity is provided for, although being suitable for low pressure output, the effort on the operating handle or the like would become excessive if required to work at high pressure.

The primary object of this invention is to provide a hydraulic pump in which the operating effort remains approximately uniform irrespective of the output pressure.

The invention will be described by way of example with reference to the accompanying dia-grammatic drawing.

According to the invention, a spring loaded by-pass valve is arranged in a by-pass which communicates with the respective ends of the double acting pump cylinder, said valve is acted upon by the delivery pressure existing in the delivery line or high pressure side, and the pressure at which the by-pass valves open, is determined by the force exerted by the spring, whereby the volume displaced by the pump becomes smaller when the pressure reaches a predetermined value, thus preventing a maximum working effort being exceeded. This maximum effort corresponding with the pressure at which the by-pass valve opens and is set by means of the spring.

A feature of the invention, is that it can be applied to a double acting pump having two or more pump cylinders in which a separate spring loaded by-pass valve arranged in a by-pass is operatively connected to each individual double acting pump, and the tension of the springs provided in the by-pass valves may be so predetermined, that as the pressure of the pump increases the by-pass valves are opened in succession.

Referring to the drawing which shows dia-grammatically a simple hand operated two cylinder double acting pump.

The pump body 1 is provided with two parallel pump cylinders 2, 3, each containing a piston 4, 5, which reciprocate in opposite directions by having their piston rods 6, 7, formed with a toothed rack 8, 9, which are in constant engagement

5 with a pinion 10 at diametrically opposite positions. Said pinion 10 is fixed to a shaft 11 which in turn is rotatably mounted in the pump body 1, and a handle 12 is keyed to said shaft 11 for manually operating the pump.

The pump body 1 has a common inlet 13 which communicates by way of conduits 14, 15, with the pump cylinders 2, 3. Spring loaded inlet valves 16, 16^a are arranged in the conduit 14 at 10 the respective ends of the pump cylinder 2 and spring loaded discharge valves 17, 17^a are provided in conduit 18 at each end of the pump cylinder. Spring loaded inlet valves 19, 19^a are arranged in conduit 15 at opposite ends of the other pump cylinder 3 and spring loaded discharge valves 20, 20^a are provided in conduit 21 at each end of said pump cylinder 3. These said inlet valves 16, 16^a and 19, 19^a and discharge valves 17, 17^a and 20, 20^a are arranged in the 15 usual manner for the delivery of fluid by way of the conduits 18, 21 to a common outlet port 22.

A separate by-pass 23 communicates with the discharge outlets of the pump cylinder 2 and another by-pass 24 communicates with the discharge outlets from the pump cylinder 3.

25 A by-pass valve 25, 25^a is contained in each by-pass 23, 24 and so arranged that the valve stems 25^b of valves 25, 25^a extending from one face of the valve terminates in the respective delivery conduits 18, 21 of the high pressure side of the pump. The stems 25^c extending from the opposite face of the valves 25, 25^a each terminate into a disc shaped head 25^d chamber 26, 26^a which communicate with the low pressure side or 30 inlet 13 of the pump by way of conduits 27, 27^a connected to conduits 14, 14^a. Each said by-pass valve 25, 25^a is spring loaded by means of a helical spring 25^e contained in the low pressure chambers 26, 26^a which act upon the heads 25^d 35 of the respective valve stems 25^c in such a manner, that the valves 25, 25^a remain closed at normal pressure. These two springs 25^e are of a different tension, so that, as the pressure increases the valve fitted with the weaker spring is opened 40 first.

In operation the effort applied to the handle 12 forces liquid from the low pressure side 13 to the high pressure side 22 in the usual manner. As the pressure increases a point is reached at 45 which the lever effort reaches a maximum in the delivery line.

The areas of the valve stems 25^b are arranged in conjunction with the tension of the springs, so that, as the pressure reaches a predetermined maximum which corresponds to the maximum

lever effort the by-pass valve fitted with the weaker spring, for example, say valve 25, opens thereby reducing the capacity of its companion pump by reason that fluid is allowed to flow through said valve to opposite of the pump cylinder 2, thus the lever effort is reduced. As the pressure increases in the high pressure side the second by-pass valve 25^a is forced off its seating when reaching a predetermined maximum when a similar operation takes place with the second pump as hereinbefore described with reference to by-pass valve 25 when fluid is free to flow past the valve 25^a by way of conduit 24 to the respective ends of the pump cylinder 3.

By this arrangement the lever effort does not at any time exceed a predetermined force, thus the variation of the effort applied to the lever is comparatively small throughout the whole time of pumping, by reason that the volume displaced by the pump is reduced in proportion to the increased pressure.

I claim:

1. A pump comprising in combination a pump body containing at least two pump cylinders, conduits for communicating respective ends of the pump cylinders with the supply and discharge sides of the pump and a by-pass communicating with the ends of each individual pump cylinder and a passage leading to the discharge conduits, inlet and discharge valves closing the inlet and discharge passages leading to and from the respective ends of the pump cylinder, common actuating means operatively connected to said pistons, and a separate spring loaded valve provided with a stem closing the passage in the by-pass between the ends of each cylinder and the stem of

each said spring loaded valve closing the passages between the discharge conduit and by-pass conduit in said valve body.

2. A pump according to claim 1 including a piston and piston rod in each pump cylinder in which the effect of working area on said piston and piston rod and the loading of each spring loaded valve closing the passages in the by-pass is determined by the requisite reduction of capacity when each said spring loaded valve is to open.

3. A pump according to claim 1 including at least one additional cylinder in the pump body.

4. A pump according to claim 1 including unequal loading of the spring valves closing the passages in the by-pass.

5. A pump according to claim 1 including loading chambers in said pump body which communicate with the supply side of the pump and a helical spring arranged in each loading chamber for acting upon the valve closing the by-pass between respective ends of each pump cylinder.

DOUGLAS GERHARD BOOTH.
